UNITED STATES PATENT OFFICE.

RALPH S. BONILLA, OF NEW YORK, N. Y.

LOCK.

Application filed February 6, 1922. Serial No. 534,480.

To all whom it may concern:

Be it known that I, RALPH S. BONILLA, a citizen of the United States, residing at New York, in the county of New York and State of New York, have invented certain new and useful Improvements in Locks; and I do declare the following to be a full, clear, and exact description of the invention, such as will enable others skilled in the art to 10 which it appertains to make and use the same.

My invention relates to improvements in locks and more particularly to those used on doors, the principal object being to provide a novel association of tapered lugs and sockets for tying the lock casing and the strike or keeper together, so as to prevent them from being pried or "jimmied" apart to release the bolt.

20 A further object of the invention is to provide for obscuring and protecting one of the attaching screws of the lock casing, by means of a rotary disc or "roll-back" which is used for operating the bolt, said disc or "roll-back," however, being provided with an opening for alinement with another opening in the front of the casing, making the screw accessible for driving or detachment by authorized persons.

30 A still further object of the invention is to provide a construction whereby the attaching screws for the strike or keeper are disposed at different angles so as to more securely hold this part to the door frame.

35 With the foregoing in view, the invention resides in the novel subject matter herein-after described and claimed, the description being supplemented by the accompanying drawings:

40 Figure 1 is a perspective view of the lock casing with its back plate removed to illustrate the "roll-back" and associated internal parts.

45 Figure 2 is a perspective view of the back plate for the casing and the key operated finger mounted thereon for controlling the bolt independently of the "roll-back."

Figure 3 is a perspective view of the strike or keeper.

50 Figure 4 is a horizontal sectional view. Figure 5 is a perspective view of the cas-

ing with most internal parts removed therefrom.

In the drawings above briefly described, the numeral 1 designates a horizontally elongated lock casing provided with a solid front wall 2 and with a removable back plate 3 secured in place by a screw 4. The plate 3 is somewhat shorter than the casing 1 and is provided with a tongue 5 at one end which is received in a beveled throat 6 at the inner end of the opening 7 which is formed in one end of the lock casing for guiding the bolt 8. The tongue 5 and the single screw 4 effectively hold the back plate 3 in place against suitable lugs 9 in the casing.

At the end of the back plate 3, adjacent the bolt 8, and spaced inwardly from the adjacent end surface of the casing 1, the latter is provided with a lateral flange 10 having screw holes 11, said flange being adapted to be inset in the edge of a door as indicated at 12 in Figure 4. The back of the casing, between the flange 10 and the adjacent end of said casing, is formed with upper and lower tapered sockets 13 which are positioned one above and one below the bolt 8, these sockets being formed in the unusually wide end wall of the casing so that they are completely surrounded by solid metal.

The strike which co-acts with the bolt 8, includes a vertical strike plate 14 having a bolt-receiving keeper 15 at one vertical edge and provided on its opposite vertical edge with a lateral flange 16 having upper and lower countersunk screw holes 17 and an intermediate countersunk screw hole 18, the latter being formed through the central portion of the flange 16 which is externally beveled as indicated at 19, toward the plate 14.

As will be clear by reference to Figure 4, the axis of the opening 18 is at right angles with the beveled surface 19, with the result that the screw 20 which passes through this opening in securing the strike to the door frame will be oblique with respect to the screws passing through the openings 17, giving much more holding power than could be otherwise obtained. For additionally securing the strike in place, another oblique attaching screw 21 is passed through an opening 22 in a boss 23 formed on the plate

14 within the keeper 15, said boss having a beveled outer surface at right angles to the axis of the opening 22 at such an angle as to permit the screw 21 to be readily driven through the open end of the keeper 15. The direction taken by this screw draws the strike tightly in place and in conjunction with the other screws, holds said strike securely on the door frame.

10 Above and below the beveled portion 19 of the flange 16 and at the juncture of this flange with the plate 14, the latter is provided with a pair of lateral tapered lugs 24 which are adapted for reception in the 15 tapered sockets 13 as shown in dotted lines in Figure 4, when the door 12 is closed. It will thus be seen that there is no possibility of prying or "jimmying" the lock and the strike apart to release the bolt 8. The 20 tapered formation of the lugs and sockets, insures that they shall properly engage each other even though the door may sag or shrink to some extent.

The numerals 25 designate a pair of 25 spring-pressed rods extending inwardly from the bolt 8 and provided with oppositely extending plates or feet 26 on their inner ends which co-act with projections 27 on a disc or "roll-back" 28 which is carried 30 by the inner end of a suitable knob 29 to be rotated at will, so as to cause one or the other of the projections 27 to engage its respective foot 26 and thereby retract the bolt 8. This "roll-back" 28 is formed with an 35 opening 28' which is adapted as shown in Fig. 4, to register with an opening 30 in the front of the casing 1 so that a screw 31 may be passed through them and driven through a lug 32, to co-act with the screws driven 40 through the openings 11, in securing the casing 1 in place, without any of the fasteners being visible. When the "roll-back" 28 is in the position which it assumes when the bolt 8 is locked by means hereinafter described, 45 the opening 29 is disposed as seen in Figure 1 and is thus out of alinement with the opening 30 so that the screw 31 is inaccessible.

The numeral 33 designates a bushing passing 50 rotatably through the back plate 3 and provided on its inner end with a finger 34 which co-acts with one of the plates 26 to move said plate inwardly and retract the bolt 8, when said finger is operated by a key 55 mechanism mentioned below. The finger 34 is also adapted to lie against the plate 26 to hold it against being retracted, so that the bolt 8 may be locked in projected position, but this arrangement is shown in my co-pending application, Serial No. 433614, filed 60 December 28, 1920 and hence forms no part of the present invention. A suitable shaft 35 is connected with the bushing 33 and extends from an appropriate barrel 36 mounted 65 in the door 12 and containing means op-

erated by a key 37 for either rotating the shaft and bushing or for locking them against rotation. Here again, the parts 35 and 36 do not constitute features of the present invention and it will be understood that 70 any suitable key-controlled mechanism may be employed for operating the finger 34. In fact, in some forms of locks, this finger and its operating means may be entirely eliminated, depending solely upon the knob 29 75 and associated parts for retracting the bolt 8.

From the foregoing, it will be seen that a comparatively simple, yet a highly efficient and desirable lock has been provided, particular emphasis being laid upon the inter-engaging lugs and sockets 24 and 13 respectively, and upon the provision of the openings 28' and 30 for giving access to the screw 31.

Since excellent results have been obtained from the details disclosed, they are by preference followed, but it is to be understood that within the scope of the invention as claimed, numerous minor changes may be 90 made.

I claim:

1. In combination, a strike plate adapted to be secured to a door frame, said plate having an integral bolt keeper spaced horizontally from the inner edge of said plate and being also provided with lateral tapered lugs above and below the bolt receiving portion of said keeper; a bolt-carrying lock casing adapted to be secured to a door with one end extending beyond the edge thereof, said one end of said casing having laterally opening tapered sockets between the bolt and the upper and lower edges of the casing, said sockets being adapted to snugly receive said lugs whereby the casing and strike plate are tied together with the door in closed position.

2. A strike plate provided at one vertical edge with a bolt keeper and provided at its other vertical edge with a lateral flange, the central portion of said flange being beveled on its outer side toward said strike plate and having a countersunk screw hole whose axis is at right angles to the beveled surface, said flange also having screw holes above and below said beveled surface.

3. A lock casing containing a bolt and a rotary disc for operating said bolt, the back of said casing having a screw hole and the front of said casing being formed with an opening alined with said screw hole but normally covered by said disc, said disc being formed with an opening for registration with the opening in said casing front to permit driving of a screw through said screw hole to assist in securing the casing in place.

4. A strike plate provided at one vertical edge with a bolt keeper and provided at its other vertical edge with a lateral flange, the

central portion of said flange being beveled on its outer side towards said strike plate and having a countersunk screw hole whose axis is at right angles to the beveled ⁹ face.

5. A lock casing containing a bolt and means for operating said bolt, the back and front of said casing being formed with aligned screw holes normally covered by said oper-

ating means; said operating means being ¹⁰ formed with an opening registering with the openings in said casing when the bolt is in drawn position, to permit the driving of a screw through said openings.

In testimony whereof I have hereunto set ¹⁵ my hand.

RALPH S. BONILLA.
